Patented Dec. 26, 1972

225,601

INFANT'S DRESSING TABLE

Raymond G. Pierson, Jr., Bedford, and Charles L. Voytko, Johnstown, Pa., assignors to Hedstrom Company, Bedford, Pa.

Filed Feb. 16, 1971, Ser. No. 115,920

Term of patent 7 years

Int. Cl. D6—03

U.S. Cl. D6—177

FIG. 2

FIG. 1

FIG. 4

FIG. 3

FIG. 5

FIG. 1 is a front perspective view of an infant's dressing table embodying our new design;

FIG. 2 is a side view thereof;

FIG. 3 is a top view thereof;

FIG. 4 is a rear view thereof; and

FIG. 5 is a perspective view on a smaller scale with the top rail in its open position.

We claim:

The ornamental design for an infant's dressing table, substantially as shown.
